UNITED STATES PATENT OFFICE.

HORACE D. GRANGER, OF AVON, CONNECTICUT, ASSIGNOR OF ONE-HALF
TO EDWARD SHELTON, OF HARTFORD, CONNECTICUT.

HINGE.

SPECIFICATION forming part of Letters Patent No. 602,846, dated April 26, 1898.

Application filed May 29, 1897. Serial No. 638,807. (No model.)

To all whom it may concern:

Be it known that I, HORACE D. GRANGER, a citizen of the United States of America, residing at Avon, in the county of Hartford and State of Connecticut, have invented a certain new and useful Improvement in Hinges, of which the following is a description, reference being had to the accompanying drawings, wherein—

10 Figure 1 is a face or flatwise view of a hinge embodying said improvement. Fig. 2 is an edge view of the same hinge which is shown in Fig. 1.

15 The object of the improvement is the production of a hinge susceptible of being made of pieces or sections of round wire, having features of novelty hereinafter described and claimed.

20 In the accompanying drawings the letter A denotes one hinge-half as a whole, and the letter B denotes the other hinge-half as a whole.

The letter c denotes the hinge-pin.

25 Each of the hinge-halves is composed of a single piece of round wire formed into a figure of the desired and efficient shape. In the hinge-half A the letter a denotes the sides of this figure, practically the skeleton of a hinge-leaf. This same piece of wire is twisted into

30 coils a', completely encircling the hinge-pin, after which it is formed into the skeleton of a second leaf a², extending in the same general direction (a slight extension answers the purpose to a degree) as the larger leaf and contained within the same. In like fashion 35 the letter b denotes the sides of the skeleton leaf in the hinge-half B. b' denotes the formation thereof into coils encircling the hinge-pin, and b² denotes the formation thereof into the secondary leaf extending outward within 40 the larger leaf.

The letters d denote staples for fastening this sort of hinge into place for use.

I claim as my improvement—

45 The combination of the hinge-pin with the two hinge-halves each made of a single piece of round wire extended into a leaf, twisted into coils completely encircling said pin and also formed into a second leaf within said first-mentioned leaf and extending in the 50 same general direction therewith, all substantially as described and for the purposes set forth.

HORACE D. GRANGER.
